UNITED STATES PATENT OFFICE.

FREDERICK W. HOLDERLE AND CARL L. HOLDERLE, OF ROCHESTER, NEW YORK.

BEVERAGE COOLING AND DISPENSING APPARATUS.

Application filed January 18, 1926. Serial No. 82,033.

Our invention relates to a beverage cooling and dispensing apparatus, and has for its purpose to provide a practicable outfit of simple and economical construction, embodying a convenient arrangement of syrup or cooler and draft arm or sink units that is readily adaptable to any store arrangement.

A primary purpose of the invention is to so construct a central syrup holding and cooler compartment unit that a draft arm and sink unit is reversible, and can be attached at either end of the central unit, thus permitting the apparatus to be used on either side of a standard ice cream cabinet.

Another object of our invention is to afford a construction having maximum cooling and serving capacity, occupying a minimum floor space, and making it possible for an attendant to have access to and operate all parts quickly and conveniently.

A further purpose of the improvement is to afford a drain board which can be reversibly located adjacent to a rinsing sink at either end of a central unit, and which normally functions as a cover for part of the cooler compartment while being slidable over the rinsing sink when access is required to the cooler compartment.

An additional object of the invention is to provide a cooler compartment with a plurality of cover sections which are slidable and interchangeable, one of such covers serving as a carrier for a series of crushed fruit containers and being slidable endwise of the cooler compartment to permit access underneath, thus affording a maximum cooling chamber with easy access to any part thereof.

These and other advantages and features of the invention will appear from the following description, when read in conjunction with the accompanying drawings, the novel features being pointed out in the claims following the description.

In the drawings:

Figure 1 is a front elevation of one embodiment of our invention, showing the draft arm and rinsing sink unit in one position in full lines and in its alternative position in dotted lines;

Figure 2 is a plan view illustrating the draft arm conductor pipes in dotted lines;

Figure 3 is an end elevation looking at the left hand end of Figure 1;

Figure 4 is a similar view looking at the right hand end of Figure 1;

Figure 5 is a longitudinal vertical sectional view on line 5—5 of Figure 4, with parts in elevation;

Figure 6 is a similar view with the cover sections moved endwise to expose the right hand end of the cooler compartment;

Figure 7 is a sectional view on line 7—7 of Figure 2, and

Figure 8 is a sectional view on line 8—8 of Figure 2.

Referring more particularly to the drawings, in which like reference characters refer to similar parts in the several views, the structure herein disclosed, which is intended merely as exemplary of various commercial embodiments of the improvements, includes a central, or syrup containing and cooler compartment unit indicated generally at 1, and an end, or draft arm and rinsing sink unit 2. The latter is attached by any suitable means at one end of the central unit, as shown in Figure 1, and this combination of units affords an outfit that can be used in conjunction with a standard ice cream cabinet to serve as a complete soda water and ice cream dispensing apparatus.

The location of the ice cream cabinet and other conditions in various stores make it necessary sometimes to reverse the relationship of the central and end units referred to, and with this in view, these parts are made independently and so constructed at their meeting faces that the draft arm and rinsing sink unit may be attached at either end of the syrup, or central, unit, as shown in dotted and full lines in Figure 1. This requires only a change in position of the leg 3 which is permanently attached to the end unit 2, and after the position of the latter is determined, it is fixedly attached to the central unit by screwing it thereto or by other suitable fastening instrumentalities. The central unit includes a series of syrup containers and pumps 4 at the rear, beneath which is located a refrigerating machine 5 of any conventional construction, while arranged in front and at one end of the refrigerating machine 5 is a cooler compartment 6 in which bottled goods and other articles may be kept cold until required for use.

The end unit includes draft arms 7 and a rinsing sink 8, the draft arms being fed from conductor pipes 9 which lead upwardly from a point at the middle of the central unit 1, so that the pipes 9 can be connected

to the draft arms 7 with equal facility at either end of the central unit 1, regardless of which end the draft arm unit 2 is located.

10 designates a drip pan under the draft arms 7, and 11 is a flange on the central section 1 adapted to overlap the adjacent wall of the end section. 12 and 13 designate the rear and front edges of the opening in the cooler chamber, affording guideways for the 15 cover sections. The rinsing sink 8, the top of which is flush with the top of the cooler compartment, is cut away in its side wall adjacent to the cooler compartment, affording unobstructed front and rear walls 14 and 15 which align with and are continuations of the aforesaid walls 12 and 13, so that the top of the rinsing sink affords a 20 guideway for the slidable cover section of the cooler compartment when access to the latter is desired.

The opening in the cooler compartment is normally closed by two cover sections, one of which consists of a drain board 16 and the other of which is designated at 17 and 25 carries a series of crushed fruit jars or containers 18 that extend downwardly into the cooler compartment. The cover section 17 overlaps the adjacent end 18 of the drain board when the parts are in normal position, 30 as shown in Figure 2, and the opposite end 19 of the drain board overlaps the joint between the central and end sections so as to insure any water or waste liquid draining into the sink.

35 When access is desired to the portion of the cooler compartment beneath the drain board 16, the latter is moved along until it occupies a position over the rinsing sink, as shown in Figure 6. Also if access is desired to the portion of the cooler compartment beneath the jar supporting section 17, the latter is moved along until it occupies the position also shown in Figure 6. In this manner, every part of the cooler compartment 40 can be conveniently and quickly reached. The cover sections 16 and 17 are interchangeable, and if the end section 12 is secured in the position shown in dotted lines in Figure 1, the cover section 17 normally 45 occupies the position shown in Figure 6 while the drain board 16 is positioned at the other end of the central unit and is reversed, so that it will still occupy the same relation to the cover section 17 while being adapted 50 for slidable movement over the rinsing sink when the latter is positioned to the right of the central unit. By locating the crushed fruit containers 18 in the cover section 17, they are conveniently accessible at all times, 55 and their contents are maintained cold while at the same time they occupy no additional space and do not interfere with the use of the cooler compartment to its maximum capacity.

60 While the invention has been described

with reference to a particular construction, it is not confined in its practical application to the precise arrangement and details shown, and this application is intended to cover any 70 modifications or departures that come within the intended purposes of our improvements or the scope of the following claims.

We claim:

1. In a beverage cooling and dispensing apparatus, the combination with a central 75 cooler unit, of a reversible sink and draft arm end unit attachable at either end of the central unit, and a drain board reversibly positionable on the cooler unit so as to cooperate with a sink and draft arm unit at 80 either end of the cooler unit.

2. In a beverage cooling and dispensing apparatus, the combination with a central cooler unit having both ends similarly constructed, of an independent sink and draft 85 arm unit having both ends similarly constructed whereby the sink and draft arm unit is attachable at either end of the central unit, and a drain board reversibly positionable on the cooler unit so as to cooperate 90 with a sink and draft arm unit at either end of the cooler unit.

3. In a beverage cooling and dispensing apparatus, the combination with a central 95 cooler unit, of a reversible sink and draft arm unit attachable at either end of the central unit, and draft arm conductor pipes extending from the middle of the cooler unit whereby they can be brought into operative relationship with a draft arm unit at either 100 end, and a drain board reversibly positionable on the cooler unit so as to cooperate with a sink and draft arm unit at either end of the cooler unit.

4. In a beverage cooling and dispensing 105 apparatus, the combination with a cooler compartment and rinsing sink, of a cover for the cooler compartment consisting of a drain board that is slidable over the sink.

5. In a beverage cooling and dispensing 110 apparatus, the combination with a central unit having a cooler compartment, of a reversible sink and draft arm unit that is attachable at either end of the central unit, and a cover for the cooler compartment 115 consisting of a slidable and reversible drain board that is positionable over either end of the cooler compartment adjacent to the sink and slidable to a position over the sink to permit access to the cooler compartment.

6. In a beverage cooling and dispensing apparatus, the combination with a cooler compartment, of a sink adjacent to one end of the cooler compartment, the cooler compartment having an opening of which the front and rear edges constitute guideways forming continuations of the front and rear walls of the sink whereby the cooler compartment cover is slidable over the sink to 120 permit access to the cooler compartment.

7. In a beverage cooling and dispensing apparatus, the combination with a cooler compartment, of a slidable cover for the cooler compartment, and a container mounted in said slidable cover and extending down into the cooling compartment.

8. In a beverage cooling and dispensing apparatus, the combination with a cooler compartment, of a container holder constituting a cover for the cooler compartment and movable to permit access thereunder to the compartment.

9. In a beverage cooling and dispensing apparatus, the combination with a central cooler unit having a cooler compartment, of a reversible sink and draft arm unit attachable at either end of the central unit, a slid- 15 able drain board constituting a cover for the cooler compartment, and a slidable container holder also constituting a cover for the cooler compartment, the drain board being reversible and interchangeable with the container holder to accommodate a sink at either end of the central unit.

10. In a beverage cooling and dispensing apparatus, the combination with a central cooler unit having a cooler compartment, of a reversible sink and draft arm unit attachable at either end of the central unit, a slid- 25 able drain board constituting a cover for the cooler compartment, a slidable container holder also constituting a cover for the cooler compartment, the drain board being reversible and interchangeable with the container holder to accommodate a sink at 30 either end of the central unit, and the container holder overlapping the adjacent edge of the drain board while the latter overlaps the adjacent edge of the sink when the parts are normally positioned.

11. The combination with a cooler compartment and adjacent rinsing sink, of a cover slidable along over the cooler compartment and over the sink.

In witness whereof, we have hereunto 45 signed our names.

FREDERICK W. HOLDERLE.
CARL L. HOLDERLE.
